ELECTROLYTIC CONDENSER

Anthony Frederik Peter Johannes Claassen, Eindhoven, Netherlands, assignor, by mesne assignments, to Hartford National Bank and Trust Company, Hartford, Conn., as trustee

Application February 10, 1938, Serial No. 189,878
In Germany February 13, 1937

1 Claim. (CL 175—315)

My invention relates to electrolytic condensers, and more particularly to condensers in which the electrodes are rolled, wound or folded together with the interposition of an electrolyte-absorbing material to form a condenser unit which is housed in a container.

So-called "dry" electrolytic condensers, i. e. condensers in which a dry or pasty electrolyte is carried by an absorbent layer which acts as a spacer between the electrodes, have the advantage that the series resistance is low because the distance between the electrodes is generally small and of the order of about 0.15 to 0.3 mm. In such condensers the electrolyte cannot freely flow so as to reach a breakdown point, and as a result the self-healing effect of such condensers is appreciably reduced.

In contradistinction to dry condensers, wet electrolytic condensers have the disadvantage that the series resistance is increased at certain points of the anode surface, and consequently the power factor of the condenser may become unduly high. More particularly in such condensers the cathode generally forms the container, and as the anode surface, after it has been formed, determines the capacity of the condenser this surface is generally made as large as possible, for instance by giving it a star shape, or by forming the anode of a spirally-wound band. As a result the distance from the cathode through the electrolyte to the anode varies for different points on the anode. Furthermore, in such condensers the series resistance is more or less dependent upon the temperature. On the other hand, wet electrolytic condensers have the advantage that they are self-healing to a high degree.

The object of my invention is to eliminate the above disadvantages and to produce an electrolytic condenser which has all the advantages of both dry and wet electrolytic condensers, but has none of their disadvantages.

Another object of my invention is to produce an electrolytic condenser which is self-healing to a high degree, and has a series resistance which is low and independent of temperature to a high degree.

Further objects of my invention will appear as the description progresses.

In accordance with the invention I use perforated electrodes which are wound, rolled or stacked with the interposition of an absorbent layer, and provide the condenser with a supply of a liquid electrolyte.

With such a construction the condenser not

only has a very low series resistance due to the close spacing of the electrodes, but also is self-healing to a high degree because the liquid electrolyte can readily reach all portions of the film-forming surface. This admission of the electrolyte is further improved by the fact that there will be spaces between the electrodes and the spacers as the unit is very loosely wounded.

In this way practically a wet condenser is obtained, however the advantages of the dry condenser are maintained in so far that the unit is obtained by winding electrodes in the form of foils separated by a spacer together to a unit.

In order that my invention may be clearly understood and readily carried into effect, I shall describe the same more fully with reference to the accompanying drawing, in which:

Figure 1 is a partly-sectionized view of an electrolytic condenser according to the invention; and

Fig. 2 is an enlarged view along line 2—2 of Figure 1.

The electrolytic condenser illustrated in the drawing comprises a cup-shaped metal container 8, whose upper end is provided with a protuberance 11. Secured to the lower end of the container in a liquid-tight manner by means of gasket 10, for instance of rubber, is a member 4 of insulating material having an externally-threaded projecting portion 14 which serves to secure the condenser to a panel.

Riveted to member 4 is a supporting rod 1 provided with an axial slot 15. The bottom end of rod 1 is provided with a flange 3 having a corrugated surface bearing upon gasket 10 to effect a liquid-tight seal. A lug 6 is riveted under the end of pin 1 at 5 and serves as an anode connection for the condenser.

To allow for the escape of gases developed within the container during operation, a rubber band 13 encircles protuberance 11 to normally close apertures 12 provided therein.

Supported by rod 1 is a condenser unit or roll B comprising an anode 17 and a cathode 18 in the form of metal strips, for instance of aluminum, provided with a large number of apertures 20. Between anode 17 and cathode 18 are strips 16 of liquid absorbent material, such as cotton fabric.

As shown more clearly in Fig. 2, the end of anode 17 is inserted in the slot 15, and the four strips 16, 17, and 18 are loosely wound into any desired number of turns depending upon the desired capacity. The term "loosely wound" as used herein and in the claim, is to be under-

stood to mean that the winding is so effected that the distance d between the anode 17 and cathode 18 varies generally between the thickness t of the spacer 16 and two to about three times the thickness t . Of course there will be places in the unit where the cathode and anode are in direct contact with the spacer, and where the distance between them is therefore equal to t . The winding is effected however so loosely, that at other places the distance may be even about three times the thickness t .

The anode 17 is provided with a dielectric film which may be formed either before or after it is wound into the roll. As shown in Fig. 1, the cathode 18 is provided with a lip 7 which is secured to container 8 at A, for instance by spot-welding. The container is filled to a level above the roll B with a suitable liquid electrolyte 19, such as a solution of 20 grams of borax and 20 40 grams of boric acid per liter of water.

It will be noted that because of the loose winding of the electrodes and the presence of apertures 20, the electrolyte can readily reach all portions of the filming surface and thus the condenser has high self-healing properties. Furthermore, because of the use of cathode strip 18 and anode strip 17, and because these strips are spaced apart at distances which are small and substantially constant the series resistance of the condenser is very low and does not vary to a large degree with temperature.

While I have described my invention in con-

nnection with specific examples and condensers of the roll type, it is not limited thereto but may be applied to condensers of other types, such as condensers in which the electrodes are stacked or folded. Therefore I wish the appended 5 claim to be construed as broadly as permissible in view of the prior art.

What I claim is:

An electrolytic condenser comprising a container, a condenser unit within said container 10 and forming a space between the side of the unit and the wall of the container, said unit comprising two large surface-area members acting as an anode and a cathode respectively and both being provided along substantially their entire length 15 with a large number of perforations, and layers of porous material between said members, said members and layers being loosely wound into a compact unit with the distance between adjacent surfaces of the members varying between 20 one to three times the thickness of the interposed porous layer and with spaces existing between the layers and members at some points of the unit, a liquid electrolyte filling the space 25 between the unit and the container, the perforations and the spaces between the layers and members, a conductor connected to one of said electrode members, and a second conductor connected to the other electrode member and supporting said unit from the container.

ANTHONY FREDERIK PETER
JOHANNES CLAASSEN.
